US0D1109161S

(12) **United States Design Patent** (10) Patent No.: **US D1,109,161 S**
(45) Date of Patent: ** Jan. 13, 2026

(54) **DISPLAY SCREEN WITH GRAPHICAL USER INTERFACE FOR AVIONICS**

(71) Applicant: **Archer Aviation Inc**, San Jose, CA (US)

(72) Inventors: **Pedro Roberto Paterson Carleial**, Los Altos, CA (US); **Jeffery Scott Greenwood**, Boulder Creek, CA (US); **Ali Taleb**, San Jose, CA (US); **Ricardo Katsumi Otani**, Milpitas, CA (US)

(73) Assignee: **Archer Aviation Inc.**, San Jose, CA (US)

(**) Term: **15 Years**

(21) Appl. No.: **29/872,708**

(22) Filed: **Mar. 17, 2023**

(51) LOC (15) Cl. **14-04**

(52) U.S. Cl.

CLAIM

The ornamental design for a display screen with graphical user interface for avionics, as shown and described.

DESCRIPTION

The sole FIGURE is a front view of a display screen with graphical user interface for avionics showing our new design.

The broken lines of uneven length surrounding the design show the display screen and form no part of the claimed design. Broken lines of even length illustrate portions of the display screen with avionics graphical user interface for avionics that form no part of the claimed design.

1 Claim, 1 Drawing Sheet
